UNITED STATES PATENT OFFICE.

LUTHER E. GRONSETH, OF DULUTH, MINNESOTA.

CHECK-WRITER.

1,349,880.

Specification of Letters Patent. Patented Aug. 17, 1920.

Application filed September 14, 1918. Serial No. 254,074.

To all whom it may concern:

Be it known that I, LUTHER E. GRONSETH, a citizen of the United States, residing at Duluth, in the county of Saint Louis and State of Minnesota, have invented certain new and useful Improvements in Check-Writers, of which the following is a specification.

The subject of this invention is a check writer, and the main object contemplated by the invention is the provision of a check writer which will write a complete check.

Another object within the contemplation of the invention is the provision of means for mounting type to be shifted into rows for printing upon the check.

A still further object of the invention is the provision of means for shifting the type.

A further object within the contemplation of the invention is the provision of means for resetting the machine when a check has been written.

Another object is the provision of means for locking certain of the type or all the type to repeat.

A still further object of the invention is the provision of a simple, durable, and efficient check writer.

With the foregoing and other objects in view which will appear as the description proceeds, the invention resides in the novel arrangement and construction of parts set forth in the description and claimed in the claims, it being understood that changes in the structural arrangement and combination of parts may be made within the spirit of the invention.

A practical embodiment of the invention is shown in the accompanying drawings, wherein:

Figure 1 is a plan view of a check writer constructed in accordance with the invention;

Fig. 2 is a rear elevation of the same with the platen removed;

Fig. 3 is a side elevation with the side plate of the casing removed;

Fig. 4 is a plan view with the key-board or top plate removed;

Fig. 5 is a detail view partly in side elevation and partly in section of a type bar and type actuating wheel;

Fig. 6 is a detail view in elevation of the lever and parts operated thereby;

Fig. 7 is a view partly in plan and partly in section of the key;

Fig. 8 is a detail view partly in elevation, partly in section, of a type supporting bar;

Fig. 9 is a detail view in elevation, partly in section of a key;

Fig. 10 is a perspective view of a disassembled key;

Fig. 11 is a detail plan view of a pawl, a fragment of a ratchet bar being shown.

Referring to the drawings by numerals of reference:

The operative parts of the device are housed in a suitable casing 1 having a top plate or key-board 2 which key-board is provided with longitudinally extending slots arranged in transverse rows. Of these slots, the upper row 3 is positioned toward the right hand side of the machine and buttons 3' are slidable therein for the purpose of shifting type to print the date on a check, as will be hereinafter described. The buttons 3' may be most conveniently made as illustrated in Figs. 9 and 10, with a T block 3'' provided with a threaded stud adapted to screw into a recess in the knurled button portion and with a shank 3''' formed for threaded engagement with the T block.

The second row of slots 4 are spaced longitudinally from the slots 3 and buttons 4' are slidable in these slots for the purpose of shifting type to print the payee's name upon a check. There are also in this row, and at the right hand end thereof, slots 3'' in which slide buttons 3'' for the purpose of shifting type to print, in numerals, the amount of the check.

A third row of slots 5 is spaced longitudinally from the second row and buttons 5' are slidable in these slots for the purpose of shifting type to print in the written amount of the check.

The rear plate 6 of the casing is movable slightly inwardly, by means hereinafter described, for the purpose of permitting the set type to protrude through the plate when the type is to be inked and the check brought against the type for the purpose of producing an impression thereof. In order that the type may protrude through the rear plate 6 and be brought in contact with the check, rows of slots 6' extend transversely of the rear plate.

Within the casing is placed a suitable supporting frame in the side bars 7 of which are secured horizontally disposed, transversely arranged shafts 8. Mounted on each of these shafts and extending rearwardly therefrom is a series of type supporting bars 9 the forward ends of which are bifurcated for a short distance longitudinally, and these ends are apertured transversely to receive the shafts 8. Also mounted on these shafts and rotatable thereon within the bifurcated forward end of each type bar 9 is a chain wheel 10, herein shown as a sprocket wheel.

Passing about each wheel 10 and resting on its type bar 9 is a chain 11, some of the links of which, indicated at 11' are type. As will be seen most clearly in Fig. 3, these bars are so arranged that by rotating the wheels the chains will be moved rectilinearly, longitudinally of the bars and the type arranged in rows extending horizontally and spaced vertically apart.

For the purpose of moving the chains about the wheels and along the type bars 9, angularly formed arms 13 extend downwardly and rearwardly from each button and have their rearmost ends pivotally secured to the chains 11 so that, by sliding a button along its slot the chain may be moved to bring any type desired in position at the rear end of the type bar 9 and before the proper slot 6'.

That the buttons may be moved to positions to bring the proper type into position to print, characters are arranged beside each slot in the key board and, in order that a button may be brought to rest and retained at a position corresponding to a selected character, ratchet bars 14 are arranged longitudinally of the supporting frame and beside the slots, and the attenuated ends of these bars are pivotally secured in supporting bars 15 which extend transversely of the frame and are positioned to underlie the space between the ends of the rows of slots. A pawl 16 is secured to the depending neck of each button and is adapted to contact its ratchet bar to permit the button to be moved toward the rear end of the machine but to normally prevent its return toward the front end of the machine. As will be understood, the teeth of the ratchet bars are so spaced as to hold the buttons at each character marked upon the key board which characters are so arranged as to bring the corresponding type to the ends of the type bars and in position before the slots 6'.

After the type has been moved into position as just set forth, the check is placed on the plate or platen 17, the lower edge of which is hingedly connected to the lower edge of the rear plate 6, and a lever 18, which rises from one end of a horizontally disposed rock bar 19, which bar is journaled within the casing 1 at the rear end and

near the bottom thereof, and which lever extends above the key-board 2, passing through a slot formed in the key-board, is grasped and thrown toward the front of the machine to bring the platen in contact with the type and print the check.

To swing the platen about its hinge, arcuate links or bars 20 are connected to the platen near each end thereof and extend through slots formed in the rear plate 6 having their other ends connected, the one to the lever 18, and the other to an arm 21 which rises from the other end of the rock bar 19.

When the platen 17 is swung to contact the type, it also becomes necessary to move the back plate 6 inwardly that the type may protrude through the slots 6' and be in-position to be met by the platen. For this purpose a rock shaft 22 extends transversely of the machine adjacent the back plate and has its ends journaled in the side plates of the casing. Fast on this shaft are the cam plates 23, one adjacent the lever 18 and the other adjacent the arm 21. Each plate is provided with a cam groove into which projects the angled end of a bar 24 which is secured to and projects inwardly from the rear plate 6. Each cam plate is also formed with an upstanding yoke 25 which normally straddles a wiper arm 26 extending from the lever 18 and the arm 21, respectively. Upon initial movement of the lever 18 and arm 21, the wiper arms 26 throw the cams to remove the cam faces 25' from contact with the rear plate 6 and, through the cam groove and rods 24, draw the plate inwardly.

An ink pad 29 may be supplied on the back plate 6 and a carriage bearing ink rollers 30 may travel in slots 31 formed in said rear plate. This carriage may be reciprocated in any of the usual and well known ways but, as the same forms no part of the present invention, specific means for operating the carriage have not been shown but the same may be operated by hand.

After the check has been printed it becomes necessary to return the type and the buttons to their normal positions. To accomplish this coil springs 32 are provided in each wheel 10 and one end of each spring is secured to its respective shaft 8 while the other end is secured to its wheel 10 in the usual and well known manner of such structures.

For the purpose of releasing the pawls 16 from the ratchet bars 14 so that these springs may operate to return the parts to normal positions, rock shafts 33 extend transversely of the frame, in which they are journaled, and are positioned in the spaces between the rows of slots. Each of these shafts has a series of spaced projecting fingers 34 arranged longitudinally of the

shaft, and each finger contacts the under face of a ratchet bar and is adapted to rock the ratchet bar and lift its serrated edge when the rock shaft is rocked in one direction. When the ratchet bar is rocked upwardly it is disengaged from the pawl 16 which immediately springs beneath the ratchet bar under the action of the spring 35, its movement being limited by the stop 16' formed on the pawl. The springs 32 are now free to act and draw the type and buttons to normal position. As the ratchet bars stop short of the positions of rest of the buttons, the bars gravitate to normal position when the pawls have passed from under them and are again in position to contact the pawls when the buttons are once more moved.

To rock the rock shafts 33 a crank arm 20 extends from each rock shaft and is connected by a link 37 to a crank 38 which is supported on the frame near the rear end of the machine. Each crank 38 is in position to be struck by a cam lug 41 which extends laterally from the arm 21. When the arm 21 is swung to normal position the cam lug engages the ends of the cranks 38 and swings them toward the rear plate 6, thus, through links 37 and cranks 38, rocking the shafts 33. Upon swinging the arm 21 in the opposite direction, the rounded off ends of the cranks 38 are engaged by the curved cam face of the lug 41 and are moved so slightly as to have no operative effect upon the shafts 33.

To provide repeat mechanism, arms 46 extend radially from each rock shaft 33, at diametrically opposite positions near one end thereof, and are in position to be struck by plungers 42 carried in blocks 43 which are secured to the top plate 2 and which plungers project downwardly through apertures formed in the plate. The plungers are retained in normal position and out of contact with the arms 46 by coiled springs 44 which surround the plungers and are confined between the upper faces of the blocks 43 and buttons 42' attached to the upper ends of the plungers. One plunger 42 of each pair of plungers is formed with an annular groove 42" adapted to be entered by a resiliently actuated detent 45 when the plunger is forced to its lowermost position to depress its arm 46 and rock the shaft 33. The detent 45 is preferably located in a bore or pocket formed in the block 43.

When the plunger 42 is forced downwardly until the detent 45 engages in the groove, it contacts the arm 46 positioned immediately below it and depresses it to the position shown in dotted lines in Fig. 7, thereby rocking the shaft 33 and swinging crank arm 36 to draw crank 38 to a position where the lug 41 will not strike it in returning the arm 21 to normal position, as seen

in dotted lines in Fig. 7. This will prevent rocking of the shaft 33 and of racks 14 which will keep the pawls 16 in contact with the racks and so hold the type in set position.

The other plunger 42 of each pair of plungers is forced downwardly to depress the arm 46 immediately beneath it and, by rocking the shaft 33, force the other arm 46 against the companion plunger 42 and force the plunger upwardly, releasing the detent 45 from the groove 42" and restoring the parts to normal position.

It is believed that, from the foregoing description the operation of the device will be apparent to persons skilled in the art without a special and extended explanation thereof being appended.

Having thus described the invention, what is claimed as new and sought by Letters Patent, is:

1. A check writer, embodying a casing, a supporting frame within the casing, tiers of movable type supported in the frame, means for moving selected type to operative position, a platen, means for drawing the platen against the type, and means controlled by the platen moving means for returning the type to normal positions.

2. A check writer, embodying a casing, tiers of movable type supported in the casing, means for moving selected type to operative position, means for locking the type moving means to hold the type in operative position, a platen, means for drawing the platen against the type, and means controlled by the platen moving means for returning the type and type moving means to normal positions.

3. A check writer, embodying a casing, tiers of movable type supported in the casing, means for moving type to operative position, means for locking the type moving means to hold the type in operative position, a platen, means for drawing the platen against the type, mechanism controlled by the platen moving means for unlocking the type moving means, and means controlled by the locking mechanism for returning the type and type moving means to normal position.

4. A check writer, embodying a casing, tiers of movable type within the casing, means for moving type to operative position, means for locking the type in a selected tier in operative position, a platen, means for drawing the platen against the type, and means controlled by the platen moving means for returning the type of the other tiers to normal position.

5. A check writer, embodying a casing, tiers of movable type within the casing, means for moving type to operative position, means for locking the type in a selected tier in operative position, a platen, means for drawing the platen against the type, and means controlled by the platen moving means for returning the type of the other tiers to normal position.

6. A check writer, embodying a casing, tiers of movable type within the casing, means for shifting type to operative position, means for locking the type shifting means, a platen, a lever for drawing the platen against the type, mechanism controlled by the lever for releasing the lock-

ing means, and means controlled by the locking means for returning the type and type moving means to normal position.

In testimony whereof I hereunto affix my signature.

LUTHER E. GRONSETH.
